Primary Examiner — Karen S Acker*Assistant Examiner* — Wendy Arminio(74) *Attorney, Agent, or Firm* — Schwabe Williamson & Wyatt(57) **CLAIM**

We claim an ornamental design for a bottle handle, as shown and described.

DESCRIPTION

FIG. 1 is a perspective view of a bottle handle, showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view of the bottle handle, shown attached to a bottle.

The broken lines are included for illustrating environmental structure and form no part of the claimed design.
